ROTARY SWITCH WITH FLOATING
CONTACT ARM

Roderic D. Taylor, Pacific Palisades, Calif.

Application August 26, 1949, Serial No. 112,477

10 Claims. (Cl. 200—84)

1

This invention relates to rotary switches and more particularly to switches associated with rotating members, one of which is connected with a contact arm while the other is provided with a number of contacts and it has for its primary object to provide a rotary switch of the above named type which makes or breaks connection after a predetermined relative angular movement of the said members and which is operative without any appreciable reaction of one rotatable member on the other.

It is a further principal object of the invention to provide a rotary switch of the above named type in which one of the two rotary members is held in its position merely by a magnet which is under the influence of an external magnetic field, said switch being operative as soon as the second rotary member has performed a relative rotation with respect to the member held by the magnet without producing a displacement of the same.

It is a further object of the invention to provide means permitting an operation of a rotary switch of the type above mentioned upon a predetermined angular movement without appreciable reaction or displacement of the members held in relatively fixed positions, said means consisting of an annular mercury container and a float supporting the rotatable contact arm connected with the member held in a relatively fixed position in space.

It is a further object of the invention to provide means for holding one of the members by means of the magnetic force of the earth said means consisting of a series of magnet needles which are mounted on a shaft and which are separated by insulating mica disks covered with enamel paint.

It is a further object of the invention to provide means for supporting the contact arm of the switch which consists of a toroidal or annular mercury container, disposed around and coaxially with the axis around which rotation of the two members takes place, said container when filled with mercury carrying an annular float member fixedly connected with the contact arm of the switch, cooperating with contacts which are fixedly connected with the second rotary member.

It is a further object of the invention to provide a switch which is operative upon a predetermined angular displacement of two coaxial rotating members, one of which includes rotatable magnets held by an external magnetic field while the other member, which is subjected

to rotation around the axis of rotation of the first named member, carries contacts and an annular mercury container disposed around the axis of rotation of the members, said container being filled with mercury supporting a float member adapted to move around the common axis of the rotating members and connected with the contact arm of the switch which cooperates with contacts on the second member.

10 Further objects of the invention will be apparent from the following detailed specification.

The invention is described with reference to the accompanying drawings showing one embodiment thereof by way of example. It is however to be understood that the example shown has been selected in order to explain the principle of the invention and the best mode of applying said principle. The example shown in the 15 drawing does not illustrate further modes of application of the principle of the invention some of which are obvious to those skilled in the art, but it will be clear that modifications of the example shown will not necessarily involve a departure from the principle of the invention.

In the accompanying drawing:

Figure 1 is a sectional elevational view, the section being taken along the plane of symmetry passing through line 1—1 of Figure 4;

Figure 2 is a sectional elevational view of the upper part of the rotary switch, the section being taken along line 2—2 of Figure 4;

Figure 3 is a plan view of the rotary switch;

Figure 4 is a sectional plan view, the section being taken along line 4—4 of Figure 2;

Figure 5 is another sectional plan view, the section being taken along line 5—5 of Figure 1;

Figure 6 is another sectional plan view of the rotary switch, the section being taken along line 6—6 of Figure 2;

Figure 7 is a sectional plan view through the rotary switch, the section being taken along line 7—7 of Figure 1;

Figure 8 is an elevational view of a door panel, carrying the switch;

Figure 9 is an end view of the cap as seen from a plane indicated at 9—9 in Figure 2.

The switching device according to the invention comprises a cylindrical, tubular container 10 of non-magnetic material which may be double walled, the two walls being formed by two concentric cylindrical tubes 11, 12 spaced by suitable spacing sleeves 13 which are held by bolts 23. The tubular container may be closed 35 at its lower end by means of a threaded plug 35

or closure disk. The container is subdivided along its longitudinal axis into several compartments separated by insulating disks forming partition walls 14, 18. The first compartment may be formed by partition wall 21 in the lowermost part of the container and this compartment may contain a stop watch mechanism 15 mounted on the closure disk or plug 35 and a further mechanism which is operated by the switch, such as a counter mechanism 16, for example, the mechanism being shown as operated by a solenoid or electromagnet 17. A further disk or partition wall in the compartment contained between the two partition walls 21 and 14 may carry a jeweled thrust bearing 19 for a vertical shaft 20 carrying magnetic needles 22 or other magnets which are influenced by an external magnetic field such as the magnetic field of the earth or any other artificially produced magnetic field.

According to the invention a number of magnetic needles 22 may be mounted on the shaft 20 and between them a number of insulating disks 24 preferably made of mica and covered with an enamel paint are arranged, which disks may be carried by a sleeve 25 encircling shaft 20. The enameled mica disks increase the magnetic reluctance for the unwanted magnetic field produced between the magnetic needles.

The shaft 20 may be pointed at the end supported on the jeweled bearing 19 and the partition walls 14, 18 through which the shaft passes may be provided with sleeve bearings 20a holding the rotatable shaft 20.

The upper end of the shaft 20 supports and carries a cup-shaped member 26 which is provided with internal teeth and thus forms an internal gear wheel meshing with a planetary gear wheel 28 which engages a central gear wheel 29 mounted on a shaft 30. The gear wheel 29 may either be of a sufficient width to be kept in engagement with wheel 28 even upon a limited axial displacement or the said gear wheel may be coupled with the shaft 30 merely for rotation but may be mounted in such a way that the shaft 30 while preserving the rotational engagement with the gear wheel may slide in axial direction in a limited way.

The shaft 30 is supported by a transverse contact arm 32 which is provided with contact rollers 33 at its ends which are preferably forked. These contact rollers may contact with fixed contacts which are described below. The contact arm 32 is held by means of suitable angular supporting brackets 38 on the upper part or cover of a mercury float 34 which consists of a number of ball-shaped floats or buoyancy members 35 which have been joined by means of an annular piece 36 of arcuate cross section (Figure 5) preferably made of a translucent plastic. The axis of said annular member 36 is coincident with the axis of the shaft and of the tubular container.

The float or buoyancy bodies 35 are fixed to the annular member 36 by means of rivets or pins so that the balls and the annular member form a single float member 34 supporting the contact arm by means of the brackets 38. This float member may rotate with the shaft 30 and around the axis of the shaft.

The float member 34 is held within a toroidal container 40 of a cross section which is bowl-shaped or ovoidal with a flat bottom and an open top. It will be understood that on account of the toroidal shape of the container 40 the

opening at the top is annular. The axis of the toroidal container 40 is coincident with the axis of the shaft 30 and of the tubular container 10, so that any movement of the float 34 will only result in a relative rotational movement of the float within the container but will not change the distances or relative positions in a transverse plane passing through the axis of the shaft 30. The container is preferably made of a translucent plastic.

It will thus be clear that the float member 34 may move within the bowl shaped toroidal member 40 while rotating around the axis of the container 10 and of the shaft 30.

The toroidal container of bowl shaped cross section is filled with mercury as indicated at 41 and the float member 34 floats on and is partly submerged in the mercury held within the said container 40.

The toroidal container 40 rests on a further disk member 42 which is provided with a central sleeve-like projection 43 through which the shaft 30 may pass. The sleeve is held by means of long screw bolts 44, 45 (Figure 1) passing through sleeves 46 to the outside of the container. The screw bolts may be provided with knurled heads. The sleeves are threaded and the screw bolts may be applied against flat outer surfaces of the sleeve-like projection 43 so as to hold the latter firmly between them.

The sleeves 46 pass through slots 53 of the inner tubular container 12; the latter is held at this end by means of spring pressed spacing screws 54.

The upper end of the tubular container 10 is closed by means of a cap 48 engaging one of the tubular members 11 and seated preferably on an insulating ring 49 joining the two tubular members 11 and 12. This cap 48 is provided with a central opening at its top which is covered by a transparent disk or plate 50 preferably made of a transparent plastic which may be provided with a graduation along the periphery of a circle the center of which is located in the axis of the shaft 30 which is also coincident with the axis of the body 10. As will be seen in Figures 1 and 3 the contact arm 32 moves immediately below the said opening and it is therefore possible to observe the movement of the shaft 30 and to note if necessary the angular displacement of the contact arm 32.

The transparent disk 50 is held in place by a closure cap 51 pressed upon the cap 48.

The cap may be held in its position frictionally by means of a flat spring 67 applied against the tube 11.

On the inside of the cap 48 insulated blocks or strips 55 are mounted which carry contact springs 56 adapted to cooperate with the contact rollers 33 of the contact arm 32. These contact springs may be connected with copper inserts 58 sliding on a copper ring 59 which is held by the insulating ring 49. The copper inserts 58 are connected with the contact springs 56 by means of bolts or by wires which are passing through the cap and which are insulated therefrom.

Obviously the number of contact springs and their shape is dependent on the specific application of the floating switch. In the example shown leaf springs have been illustrated which are somewhat projecting into the interior of the cap and are pressed back by the contact rollers 33 when the contact arm 32 moves over them so as to produce good contact. The position of the spring relatively to the rollers may be adjusted by ad-

justing screws 68 which are provided in the cap and which may be adjusted in order to adjust the contact between the leaf springs and the rollers. The example shown in the drawing illustrates a construction in which contact is only established once when a certain angular deviation of the two movable members has been reached. Obviously, however, the insulated ring may be provided with a larger number of inlaid surface contacts in the manner of a commutator, over which the contact rollers 33 of the contact arm 32 may move. Each contact in this case is led to a separate terminal.

In the example shown the contact spring 56 on one side is joined to the copper insert 58 which in its turn is connected with the mercury container 40 by means of a wire 62 leading to a further terminal post 60 passing through the bottom portion of said toroidal container 40 of translucent plastic. At a second terminal post 61 passing through the bottom of said container 40 a connection may be made with the source of current by means of a wire 63. At the second copper insert 58 on the right side of Figure 2, a further connection is indicated in the form of a wire 64.

Wire 64 as shown in Figure 1 may lead to the solenoid 17 of the counter mechanism 16, the other terminal of which may be connected with the source of current by means of wire 65. Both wires may run through the hollow space between the two tubes 11, 12 and are led to the outside through an insulating sleeve 66 in the outer tube 11 which is located at an appropriate place.

If the magnetic needles are held in a certain position in space by the magnetic field of the earth and if the container 10 is secured to a rotating object which rotates around the axis of the shafts 20 and 30 which is coincident with the axis of the container 10, then it will be clear that the counter 16 and the stop watch mechanism 15 are operated as soon as the tubular container 10 has been rotated through a certain angle. Attention is called to the fact that such an angular movement has been translated by means of the gear-wheels 27, 28, 29, so that the axial angular movement of the container 10 relatively to the fixed position of the needles may be either larger or smaller than the movement performed by the contact arm 32. As an example the switch may control or register the opening of a door. The container 10 in this case is mounted vertically within a hole 69 in the door panel 70. A movement of the door to a certain extent for instance to the extent necessary for the passage of a person will then be registered by means of the counter.

It will be clear that a change of an unessential nature will not involve a departure from the invention as claimed in the annexed claims.

Having described the invention, what is claimed as new is:

1. A rotary switch comprising a tubular container, a contact arm with a slide contact moving along the inner surface of said container, peripheral contacts substantially arranged in and along the inner container surface, swept by the slide contact, a shaft connected with said contact arm, a toroidal container of bowl shaped cross section filled with a conducting liquid, fixed within said container, an annular conducting float member, floating in the liquid filled toroidal container, supporting said contact arm and in conducting connection with the same, contacts in the toroidal container provided with connecting means for

producing a connection with said float carried contact arm including the conducting liquid and float member, means for producing a relative angular movement of the tubular container relatively to the shaft and contact arm, and means for holding one of said members in a fixed position in space.

2. A rotary switch comprising a tubular container, a radial contact arm with a slide contact moving along the inner surface of said container, peripheral contacts substantially arranged in and along said inner container surface, swept by the slide contact, a shaft coaxial with the container axis, connected with said contact arm, a toroidal container of bowl shaped cross section, filled with a conducting liquid, fixedly held within said container and coaxial with the said shaft, an annular conducting float member including buoyancy members floating within the liquid in the toroidal container and supporting the said contact arm and shaft, further contacts in the toroidal container provided with connecting means for producing a connection with the contact arm including the conducting liquid and float member, a further independently supported and separately rotatable shaft coupled with the first named shaft within said tubular container and magnetized members carried by said further shaft subjected to the influence of an external magnetic field.

3. A rotary switch comprising a cylindrical tubular container, a radial contact arm within said container, an open toroidal container of bowl shaped cross section, coaxial with the cylindrical container carried by the tubular container, said toroidal container being filled with a liquid, a float consisting of buoyancy members floating in the liquid held in the toroidal container and of an annular member joining said buoyancy members, said float being coaxial with and held within the toroidal container, brackets projecting outwardly through the open portion of the toroidal container and supporting said contact arm, contacts in the interior of the tubular container cooperating with the contact arm, magnetic means for holding said contact arm under the influence of an external magnetic field, and means for producing a relative rotation between said contact arm and said tubular container.

4. A rotary switch as claimed in claim 3, wherein the contact arm is located at one end of the tubular container, a cap with a transparent plate provided with a graduation on said end of the tubular container, the graduation indicating the relative angular displacement of the contact arm and the tubular container.

5. A rotary switch comprising a double walled tubular cylindrical container, consisting of two spaced concentrically arranged tubes, a cylindrical cap at one end of the tubes carrying fixed contacts arranged along its inner cylindrical surface, a contact arm rotatable around the axis of the cylindrical tubes, sweeping over and cooperating with said fixed contacts, a toroidal container of bowl shaped cross section open at the top, held within and arranged coaxially with said tubular container, said toroidal container being filled with mercury, an annular float within said toroidal container coaxial with the same including an annular member, with a number of buoyancy bodies attached to it floating on the mercury, said contact arm being supported on said annular float by brackets passing through the open top portion of the toroidal container, a shaft in the axis of the tubular container, pro-

vided with longitudinally spaced magnetic members, and means for coupling said shaft with said contact arm.

6. A rotary switch as claimed in claim 5, wherein the shaft carrying the magnetic members is coupled with an internal gear wheel, further gear wheels meshing with said internal gear wheel, a further shaft rotatively coupled with one of the last named gear wheels, said further shaft being connected with the contact arm.

7. A rotary switch as claimed in claim 5, wherein fixed contacts are arranged at diametrically opposite portions of the cap and wherein the contact arm is disposed along a diameter of the tubular container and is bridging and connecting contacts arranged at diametrically opposite portions of the cap.

8. A rotary switch as claimed in claim 5 wherein the fixed contacts in the cap consist of leaf springs.

9. In a rotary switch as claimed in claim 5 wherein the fixed contacts of the cap consist of leaf springs, adjusting screws in the cap bearing against the ends of said leaf springs to adjust the position thereof.

10. A rotary switch as claimed in claim 2, wherein one of the contacts arranged in and along the inner container surface is connected with one of the contacts in the toroidal container contacting the conducting liquid.
